(57) **CLAIM**

The ornamental design for a push broom, as shown and described.

DESCRIPTION

FIG. 1 is a perspective view of a push broom showing my new design;

FIG. 2 is an enlarged front view thereof, the rear being a mirror image thereof;

FIG. 3 is an enlarged top view thereof;

FIG. 4 is an enlarged bottom view thereof; and,

FIG. 5 is an enlarged right side view thereof, the left side being a mirror image thereof.

The broken line showing in FIGS. 1, 3 and 4 of the portion of the mop handle, the bracket assembly connecting the handle and broom head, the bristles, the rectangular openings at the top and bottom surfaces of the push broom, and the bottom face of the push broom are for illustrative purposes only and form no part of the claimed design.
